UNITED STATES PATENT OFFICE.

JAMES SLAYTON BAKER, OF TEXARKANA, TEXAS, ASSIGNOR OF ONE-SIXTH TO ROLLIN W. ROGERS, ONE-SIXTH TO JASPER NEWTON WHITE, AND ONE-HALF TO THOMAS W. HUNTER, ALL OF TEXARKANA, TEXAS.

SIGNAL.

1,322,396.

Specification of Letters Patent.

Patented Nov. 18, 1919.

Application filed February 26, 1919. Serial No. 279,355.

To all whom it may concern:

Be it known that I, JAMES S. BAKER, a citizen of the United States, and a resident of Texarkana, in the county of Bowie and 5 State of Texas, have invented new and useful Improvements in Signals, of which the following is a specification.

This invention relates to signals and has particular reference to that class of signals 10 used in connection with the exhaust pipe of an automobile engine.

An important object of the invention is to provide in a device of the above mentioned character a means whereby the various co-operating elements thereof may be so positioned with respect to each other as to cause the exhaust gases to produce a signaling noise when escaping into the atmosphere.

A further object of the invention is to 20 provide in a device of the above mentioned character a means whereby various co-operating elements thereof may be moved to such a position with respect to each other as to permit the exhaust gases to be passed through 25 the device without being brought into contact with the sound producing elements.

A further object of the invention is to provide in a device of the above mentioned character a means whereby the exact position 30 of various co-operating elements with respect to other co-operating elements may be readily determined.

A further object of the invention is to provide a means whereby numerical indicating 35 combinations may be employed to indicate the position of various co-operating elements with respect to each other.

A further object of the invention is to provide in a device of the above mentioned character a means whereby a given numerical combination may be changed to that of other desired numerical combinations.

Other objects and advantages of the invention will be apparent during the course 45 of the following description taken in connection with the accompanying drawings.

In the drawings, forming a part of this specification and in which like numerals are employed to designate like parts throughout 50 the same,

Figure 1 is a side elevation of the device embodying my invention,

Fig. 2 is a central vertical longitudinal sectional view through the device,

Fig. 3 is a similar view to that of Fig. 2, 55

Fig. 4 is a face view of a disk,

Fig. 5 is a face view of a similar disk,

Fig. 6 is an end elevation of an intermediate section, and,

Fig. 7 is an opposite end view of the section referred to in Fig. 6.

Fig. 8 is a sectional view taken on line 8—8 of Fig. 2, and,

Fig. 9 is a diagrammatic view showing the 65 passage of the exhaust through one of a plurality of sound producing elements.

In the drawings, wherein for the purpose of illustration is shown a preferred form of my invention, the numeral 10 indicates a pipe having openings 11 arranged therein, 70 the pipe 10 being preferably formed solid intermediate the openings 11 as shown at 12. Upon the pipe 10 substantially intermediate the openings 11 there is secured an intermediate section 13 which is provided with a bypass 14 and arcuate-shaped groove 15 extending substantially throughout the circumference of the section as clearly shown in Fig. 6. The section 13 is provided diametrically opposite the bypass 14 with a duct 16 80 having a port 17 opening into the atmosphere as clearly shown in Figs. 2 and 3. Within the duct 16 at each end thereof there is suitably arranged whistles 18 and 19, which whistles are held in a desired position 85 by means of bushings 20 and 21. These bushings are retained in position by means of disks 22 and 23 which are rotatably mounted upon the solid portion of the pipe 10 and free to rotate with respect to the intermediate section 13. The disk 22 is provided with a groove 24 adapted to receive a flange 25 carried at the end of the intermediate section 13. The disk 22 is provided with a plurality of lugs 26 adapted to enter 95 corresponding notches 27 arranged within a head 28, which head is rotatably mounted upon the pipe 10 and locked against longitudinal movement by means of nuts 29. In order to support that end of the head 28 100

contacting with the disk 22 there is provided a flange 30 engaging the inner surface of the end of the head 28 as clearly shown in Figs. 2 and 3. In order to afford a communication between the bypass 14 and the interior of the head 28 there is provided an opening 31 adapted for registration with the bypass 14 and a similar opening 32 provided by the disk 23. The disk 23 is provided with an arched-shape groove 33 similar to that provided by the intermediate section and indicated by the numeral 15. The disk 23 like the disk 22 is provided with an annular groove 34 adapted for the reception of a flange 35 provided by the intermediate section 13. The disks 22 and 23 are both provided at their peripheral edges with gears 36 and 37 respectively and are adapted to mesh with a gear 38 carried by a manually rotatable stem 39, the end of which is adapted to enter apertures 40 and 41, the apertures 40 being arranged in proximity to the gear 36 and the apertures 41 being arranged in proximity to the gear 37. The disk 23 like the disk 22 is provided with a plurality of lugs 42 arranged within notches 43 carried by a head 44 similar to that indicated by the numeral 28. The head 44 is rotatably mounted upon the pipe 10 and locked against longitudinal movement by means of lock nuts 45. In order to support that end of the head 44 within which the lugs 42 are arranged there is provided a flange 46 carried by the disk 23, the flange 46 having engagement with the inner surface of the head 44 as clearly shown in Figs. 2 and 3. Upon the heads 28 and 44 bands 47 and 48 respectively are arranged. These bands are provided with numerals as clearly shown in Fig. 1 and are retained in position by means of bolts 49 passed through the ends thereof. Upon the intermediate section 13 there is arranged a band 50 which is provided with numerals corresponding to the numerals carried by the bands 47 and 48. The band 50 is secured in position by means of a bolt 51 passed through the ends thereof as clearly shown in Fig. 1. By means of a union 52 the pipe 10 is secured to the exhaust pipe 53 leading from an internal combustion engine, not shown, and by means of a similar union 54 the pipe 10 is secured to the exhaust pipe 55 leading to a muffler, not shown, if it is desired in any instance to employ a muffler.

In use, the various coöperating elements of the device normally retain their positions with respect to each other as shown in Fig. 2, thereby permitting the exhaust gases to pass through the device in the directions of the arrows thereon without coming into contact with the whistles 18 and 19 or other noise producing elements.

It will be noted that the numerals 12 car-

ried by bands 47 and 48 register with the numerals 12 carried by the bands 50 when the various coöperating elements are in the position shown in Fig. 2.

When it is desired to move the various coöperating elements to such a position as will cause the whistles 18 and 21 or other noise producing elements to be actuated upon by the exhaust gases, the end of the spindle 39 is placed in one of the apertures 40 and rotated, in which instance the gear 38 engaging with the gear 36 will cause the disk 22 to be moved to such a position as will sever communication between the bypass 14 and the interior of the head 28. When this communication has been severed, communication between the interior of the head 28 and the groove 15 is established through the opening 31. When communication is thus established the exhaust gases will be permitted to pass into contact with the whistle 18 or other noise producing element as indicated by the arrows of Fig. 3. By placing the end of the spindle 39 in one of the apertures 41 the gear 38 by rotating the spindle 39 may be made to move the disk 23 into the position diagrammatically shown in Fig. 9, in which instance communication between the head 44 and the bypass 14 is severed and the exhaust gases, assuming that communication between bypass 14 and the interior of the head 28 is established, will pass out of the head 28, into the groove 33 whereupon they are directed into contact with the whistle 19 or other noise producing element in the direction of the arrows shown in the diagrammatic illustration of Fig. 9.

By employing the adjustable bands 47, 48 and 50 it is apparent that a given combination which indicates the position of the elements as shown in Fig. 2 may be changed to various combinations, therefore, if a given combination should be generally known it would be necessary only to remove either of the bolts 49 or 51 and make a suitable adjustment of the bands to establish a new combination which would indicate the position of the elements as shown in Fig. 2.

It is to be understood that the form of my invention herewith shown and described is to be taken as a preferred example of the same, and the various changes in the shape, size and arrangement of parts may be resorted to without departing from the spirit of the invention or the scope of the subjoined claims.

Having thus described my invention, what I claim as new and desire to secure and to be protected by Letters Patent of the United States, is:

1. A device of the character described

comprising an exhaust pipe; rotatable heads mounted upon said exhaust pipe, said heads normally communicating with each other and with said exhaust pipe; an intermediate 5 section disposed between said heads, said intermediate section being provided with a duct; sound producing elements arranged within said duct; and means for rotating said heads whereby communication is severed therebetween and established between 10 said exhaust pipe and said duct, the sound producing elements being acted upon by the exhaust gases of said exhaust pipe when communication is established between said 15 duct and said exhaust pipe.

2. A device of the character described comprising an exhaust pipe; a rotatable head mounted upon and communicating with said exhaust pipe; a stationary element secured to said exhaust pipe, said stationary element being provided with a duct; a sound producing element arranged within said duct; and means for rotating said head whereby communication is established between 20 said exhaust pipe and said duct, the sound producing element being acted upon by the exhaust gases of said exhaust pipe when communication is established between 25 said duct and said exhaust pipe.

3. A device of the character described comprising an exhaust pipe; a stationary section having a bypass, a groove, and a duct, said bypass normally communicating with said exhaust pipe; a sound producing 30 element arranged within said duct; a rotatable disk; and means for rotating said disk whereby communication is severed between said bypass and exhaust pipe and established between said duct and said exhaust 35 pipe.

4. A device of the character described comprising an exhaust pipe; a stationary section having a bypass and a groove; a rotatable disk having an opening normally communicating with said exhaust pipe and bypass; means for rotating said disk whereby communication is severed between said bypass and said exhaust pipe and established between the exhaust pipe and said groove; and a sound producing element obstructing 50 the passage of said groove, said sound producing element being acted upon by the exhaust gases when communication is established between the exhaust pipe and said groove.

5. A device of the character described comprising an exhaust pipe; a stationary section secured to said exhaust pipe, the stationary section being provided with a by-

pass and a plurality of sound producing elements; and movable means for establishing 65 communication between said exhaust pipe and one of said elements through said bypass.

6. A device of the character described comprising an exhaust pipe, a stationary 70 section secured to said exhaust pipe, the stationary section being provided with a bypass and a sound producing element; a rotatable disk arranged upon said stationary section, said disk being provided with an opening 75 and a groove, the opening normally communicating with said bypass, the bypass normally communicating with the exhaust pipe, means for rotating said disk whereby communication is established between said 80 groove and bypass, the exhaust gases being directed from said exhaust pipe through said bypass into said groove to act upon said sound producing element to produce sound.

7. A device of the character described 85 comprising an exhaust pipe; a stationary section secured to said exhaust pipe, the stationary section being provided with a bypass and a groove, a disk rotatably mounted upon said section, said disk being provided 90 with an opening normally communicating the exhaust pipe with said bypass, a second disk rotatably mounted upon said intermediate section, the second named disk being provided with an opening and a groove, a 95 sound producing element obstructing the passage of the first named groove, means for rotating the first named disk to establish communication between the exhaust pipe and said groove whereby the exhaust gases 100 are directed into contact with the said sound producing element, and means for rotating the second named disk whereby communication between the groove thereof and said bypass is established, a second sound producing 105 element obstructing the passage of the second named groove.

8. A device of the character described comprising an exhaust pipe; a stationary section secured to said exhaust pipe, the stationary section being provided with a bypass and a groove, a rotatable disk mounted upon said intermediate section, said disk being provided with an opening normally communicating the exhaust pipe with said bypass, 110 means for rotating said disk whereby communication is established between said exhaust pipe and said groove, a sound producing element adapted to be acted upon by the exhaust gases passing through said groove 115 to produce sound, and means for indicating the relative position of said disk with respect to said intermediate section.

9. A device of the character described comprising an exhaust pipe; a stationary 125 section secured to said exhaust pipe, the sta-

tionary section being provided with a bypass normally communicating with the exhaust pipe; a rotatable disk mounted upon said stationary section, the rotatable disk being provided with a groove, the passage between said groove and bypass being normally severed; means for establishing communication between said groove and by-

pass; a sound producing element obstructing the passage of said groove, the sound producing element being acted upon by the exhaust gases to produce sound; and means for indicating the position of said disk with respect to said intermediate section.

JAMES SLAYTON BAKER.
